(57) **CLAIM**

The ornamental design for a carrier apparatus shell for pneumatic tube delivery system, as shown and described.

DESCRIPTION

FIG. 1 is a frontal perspective view of a carrier apparatus shell for pneumatic tube delivery system illustratively incorporating our present design;

FIG. 2 is a top elevational view thereof;

FIG. 3 is a front elevational view thereof;

FIG. 4 is a right side elevational view thereof, an opposing left side elevational view being a mirror reflection of such right side elevational view;

FIG. 5 is another frontal perspective view of the carrier apparatus shell for pneumatic tube delivery system as shown in FIG. 1, with certain illustrative features previously shown removed in order to show aspects of the design that would otherwise not be apparent;

FIG. 6 is a rear perspective view of thereof;

FIG. 7 is another frontal perspective view of the carrier apparatus shell for pneumatic tube delivery system as shown in FIG. 1, but in an unlocked configuration;

FIG. 8 is a frontal perspective view thereof, with the unlocked shell in an open configuration;

FIG. 9 is a rear perspective view thereof, with the unlocked shell in the open configuration;

FIG. 10 is a rear perspective view of the carrier apparatus shell for pneumatic tube delivery system as shown in FIG. 1 in a vertical orientation, as viewed from a first viewing angle; and, FIG. 11 is another rear perspective view of the carrier apparatus shell for pneumatic tube delivery system as shown in FIG. 1 in a vertical orientation, as viewed from a second viewing angle.

The broken lines encompassing unshaded regions in the FIG. 6 and FIG. 9 views represent the bounds of the claimed design while all other broken lines are directed to environment and are for illustrative purposes only; the broken lines form no part of the claimed design.
